UNITED STATES PATENT OFFICE.

CLARENCE LEICESTER LORRAINE, OF EAST JORDAN, MICHIGAN.

VOTING-MACHINE.

964,986.

Specification of Letters Patent. Patented July 19, 1910.

Application filed July 27, 1909. Serial No. 509,769.

To all whom it may concern:

Be it known that I, CLARENCE L. LORRAINE, a citizen of the United States, and a resident of East Jordan, in the county of 5 Charlevoix and State of Michigan, have invented a certain new and useful Voting-Machine, of which the following is a full, clear, and exact description.

The principal objects which the present 10 invention has in view are: to provide a machine for receiving and recording ballots, wherein provision is made to prevent tampering with the ballot; to provide a machine wherein provision is made for straight ticket 15 and split ticket voting; to provide a machine wherein notice is given of the registration of the vote; to provide a machine wherein duplication of the vote is prevented; to provide a machine wherein the 20 mechanism is certain, rapid and efficient; and to provide a machine wherein the voter is enabled to see his ballot deposited.

One embodiment of the present invention is disclosed in the structure illustrated in the 25 accompanying drawings, wherein like characters of reference indicate corresponding parts in all the views.

Figure 1 is a side elevation, partly in section, of a machine constructed in accordance 30 with the present invention. Fig. 2 is a front elevation, partly in section of the same. Fig. 3 is a plan view of the selecting table; Fig. 4 is a plan view of the bottom plate of the magazines wherein the ballot balls are 35 initially stored; Fig. 5 is a rear elevation of the machine, partly cut away to show the extra locking devices; Fig. 6 is a detail view in perspective of the locking devices shown in operative relation to the depositing 40 slides; Fig. 7 is a side elevation of the locking devices forming one of a series of locks; Fig. 8 is a side elevation of one of a different series of locking devices; Fig. 9 is a detail view in plan of a selecting strip; Fig. 10 is a detail view in plan of a depositing slide; Fig. 11 is a vertical section showing the 45 depositing slide having attached thereon a selecting strip, and in relation thereto the receptacles for the cast ballots, and the mechanism for adjusting the depositing 50 slides; Fig. 12 is a detail view in front elevation, partly cut away to show the vertical section of the magazine columns; Fig. 13 is

a detail view of a segment of the extracting plate; Fig. 14 shows vertical sections of the 55 receptacles for holding the cast ballots and guide chute leading thereto; and Fig. 15 is a side elevation of the receptacles for the cast ballots shown in relation with the locking strips for sealing the same; Fig. 16 is a plan 60 view in fragmentary form showing sections of the selecting table and the arrangement of the voting lever and delivery chutes connected therewith; Fig. 17 is an enlarged 65 view in detail illustrating the arrangement of the guide and supporting pillars, whereby the selecting strips 77 may be shifted or the shifting may be prevented; Fig. 18 is a detail view in perspective, of the locking mechanism for preventing the return of the 70 voting paddles under certain conditions.

In employing the present machine the ballots used are small spheres or balls. These are primarily held in magazines formed of a plurality of nearly vertical 75 tubes 16, held in any suitable frame, and resting upon a base plate 17 (see Fig. 4). The base plate 17 is slidably mounted on a frame plate 18 and is provided with ears 19, 19, which are perforated and tapped 80 with suitable screw threads to receive long screws 20, 20. The screws 20, 20, are mounted in bearings 21, 21, set up in the longitudinal frame members of the supporting frame. At the one end the screws 20, 20, 85 are provided with miter gears 22, 22, in toothed engagement with the gears 23, 23 fixedly mounted upon a shaft 24. The shaft 24 is mounted in bearings 25, 25, set out from the rear of the frame, and in the side 90 thereof, and is provided beyond the frame with a crank handle 26. By means of this construction, the successive lines of tubes 16, 16, may be advanced to register with tubular openings in a bar 27 (see Fig. 12 95 of the drawings). The bar 27 is stationary, which permits the plate 17 to advance and recede over the line of perforations formed in the bar 27. The perforations are formed in the bar 27 near the forward edge thereof, 100 and the side wall is split to provide openings 28 through which the voter may see the balls in the tubes formed in the bar 27.

Below the bar 27 is a stationary plate 29 perforated to receive small tubes 30 which 105 are screwed, driven or pressed within perfor-

lations provided therefor in the said plate 29, The ends of the tubes 30 are expanded as at 31 to receive the upper and fixed end of conveyers 32, formed of coiled wire or other suitable material which while flexible and durable will be non-collapsible, and will furnish a safe and certain path for the ball to follow when it is dropped. The tubes 30, 30, are out of line laterally with the tubular openings in the bar 27. Interposed between the bar 27 and the plate 29 is a perforated slide 33, controlled to move longitudinally and in line with the tubular openings in the bar 27 and the tubes 30. The slide 33 is provided with a series of perforations equal in number to the line of tubular openings in the bar 27. In one of the extremes of movement of the slide 33 the perforations in the slide 33 register with the tubular openings in the bar 27, while at the other extreme of movement of the slide 33 the perforations register with the tubes 30, 30.

At each operation of voting, the slide 33 is advanced from the position under the tubular openings in the bar 27 to a position over the tubes 30, 30. After each operation of voting, the slide 33 is returned to the position wherein the perforations in the slide 33 register with the openings in the bar 27. With each registration of the perforations in the slide 33 with the openings in the bar 27, the perforations in the slide 33 receive each a ball from the magazine tubes 16, 16, the metal of the slides 33 being just sufficient to contain the said ball. When the registration between the slide 33 and the tubes 30, 30, occurs, the balls carried in the perforations are deposited in the tubes 30, 30, and from them into the conveyers 32, 32. The mechanism for thus shifting the slides 33, 33, consists in a manually-operated lever 34 the handle of which is extended to within convenient grasp of the voter, while the lever is pivoted at 35 to the frame of the machine. The lever 34 is provided with an extension 36 which rests against a shoulder formed in the slide 33, by which the slide 33 is advanced to register with the tubes 30, 30. At the opposite end, the slide 33 is provided with the anti-friction roller 37 against which the cam 38 operates to return the slide 33 to the position wherein the perforations therein register with the tubular openings in the bar 27. The cam 38 is mounted upon the end of a plate 39 which is connected through a link 40 to a lever 41. The lever 41 is pivotally mounted at 42 upon the frame of the machine, and is connected by a link 43 to a quadrant 44 which is rotatably mounted on a shaft 45 fixedly engaged by a lever 46.

The lever 46 is the master lever of the machine, and is operated and controlled by the inspector of elections. With each throw of

the lever 46 which occurs after the casting of the vote, as will hereafter more clearly be set forth, the plate 39 is drawn to the position shown in Fig. 4 of the drawings, and when so drawn causes the impingement of the cam 38 upon the roller 37 to shift the slide 33 into registering position with the tubular openings in the bar 27.

As stated, the balls are deposited from the perforations in the slide 33 within the conveyers 32, 32. There are as many conveyers 32 as there are tubes 30 and depositing slides 47, 47. It is by the adjustment of the depositing slides 47 that it is determined to which of the receptacles 65, 65, the ballot ball 80 is to be delivered. The slides 47 are advanced to their normal position such as shown in Fig. 3 of the drawings, by a set bar 49, which is extended across the rear of the machine and supported upon side arms 85 50, 50. The under surfaces of the side arms 50, 50, are provided with suitable rack teeth 51 engaged with gears 52, 52. The gears 52, 52, are mounted upon a cross shaft 53 which is suitably mounted in bearings 54 at 90 each side of the frame of the machine. The shaft 53 has fixedly mounted thereon a pinion 55 which is in toothed engagement with the toothed periphery of the quadrant 44. As before stated, the quadrant 44 is secured 95 upon the shaft 45 upon which the lever 46 is mounted.

In Fig. 1 of the drawings, the mechanism just described is illustrated as disposed in the position wherein the bar 49 has been 100 advanced to move all of the depositing slides to their forward position. It is in this position that the machine rests before the selecting mechanism has been operated by the voter. In this position the notches 56, 56, 105 are brought in straight line, and the locking bars 57, 57, are placed to extend within the notches 56, thereby locking all of the depositing slides against movement. The mechanism controlling the disposition of the 110 locking bars 57 is under control of and is manipulated by the inspector of elections. When the depositing slides 47 are released, they may be moved inward from the front of the machine, either individually or collectively. If the selection be individual, this is accomplished by the voter moving each rod 47 inward, by taking hold of a pin 58 as a handle, for moving the slides 47.

Between each slide 47 is a stationary tabular strip 59 upon which is engrossed the name or device of a candidate, party, or an affirmative and a negative expression. Extended from the side of each of the slides 47 is a wire loop 60, adapted to expose within 125 the boundary thereof, one of the said names, devices or expressions. The tabular strips are divided to receive these various names and expressions, so that when the names or expressions are exposed within the loops 60, 130

nipples 61 in the slides 47 rest above one of the chutes 62, 62 which deliver the balls to the channels 63, 63, which, in turn, deposit the same upon the inclined tops 64, 64, of receptacles 65.

When the voter has manipulated the various slides 47 to cause the loops 60 on the same to register with the names and insignias of the selection, or, in other words, has made up his ticket, he then votes by catching hold of the lever 34 and moving the same in the direction indicated by the arrow in Fig. 4 of the drawings, which, as above described, results in the movement of the slide 33 from under the tubes 16, 16, to deposit the balls carried by the perforations in said slide to the tubes 30, 30 and conveyers 32, 32. The conveyers 32, 32, being held by the nipples 61 which have been by the manipulation of the voter, placed over the proper receptacles 65, 65, the balls deposited from the slide 33 are conveyed to and deposited in the chutes 62, 62, and the receptacles 65, 65.

The above, as stated, is the operation when the voter has manually and individually adjusted the slides 47, which class of voting is presumed to be the method of a non-partisan voter. For the partisan voter the operation is quicker, the slides 47, 47, being moved forward into the voting position, *en masse*. This is accomplished by manipulating the lever 66 and the quadrant 67 connected therewith, said lever and quadrant 67 being pivotally mounted at 68 upon a standard 69. The quadrant 67 is provided on its periphery with gear teeth held in toothed engagement with a pinion 70, fixedly mounted upon a shaft 71 which carries a drum 72, which has suitably secured thereon tapes 73, 73. To each of the depositing slides 47, 47, there is attached at 74 a tape 73, which tapes are each of equal length. Hence, when the drum 72 is rotated by drawing the lever 66 toward the front of the machine, the slides 47 are carried an equal distance toward the rear of the machine, placing the nipples 61, with which each is provided, over the same line of receptacles 65, 65. The tapes 73, 73 are not connected with the slides 47, except as the same are grouped in party ticket arrangement. When the slides are operated singly, the lever 66, the drum 72 and the tapes are not called in operation. In the event where the slides are disposed singly, the tapes 73 are permitted to sag into the lower part of the machine.

The lateral arrangement of the receptacles 65, 65, is consonant with the party members or party ticket. The position to which the lever 66 shall be drawn to vote the party ticket, is indicated by a plate 75 which is provided with niches 76, 76, opposite each of which is indicated the name of the party selected. Thus (referring to Fig. 3 of the drawings), should the lever 66 be moved to

the position indicated by the word "Prohibition," the slides 47, 47, would each be advanced within the machine, until the loops 60, 60, inclose the names of each of the candidates of that party for the various positions being voted upon. If the straight ticket is to be voted, the voter having so set the machine as described, by the use of the lever 66 then grasps the lever 34 and moves it as indicated, to deliver the ballot balls 75 from the magazine through the conveyers 32, 32, into the receptacles 65, 65, to which the various conveyers are so disposed to lead.

The slides 47 may be arranged in groups. In Fig. 16 of the drawings is illustrated three groups. The central group marked A is provided with a series of movable selecting strips 77, 77, illustrated more particularly in Fig. 9 of the drawings. These strips are provided with a series of holes 78, 78 to fit over the pin 58 hereinbefore mentioned. Each strip 77 is provided with a nipple 61 to which a conveyer 32 is connected. The strips 77 are provided with loops 60 as are the slides 47 on the other sections B and C of the machine. The strips 77 are movable to permit their being detached from one slide 47 and transferred to another. The strips and the slides to which they are connected are divided and guided by the upturned ends 79 of the fixed tabular strips 59. (See Figs. 3 and 17.) These upturned ends 79 are extended toward a light cross rod 80 through which is inserted a series of screws 81. (See Figs. 1 and 17.) With the interposition of the screws 81, the channels between the ends 79, 79 are closed, but with the removal of the screws 81 these channels are opened and the strips may be passed above the said ends as shown in dotted lines. (See Fig. 17.) The reason for this construction is to provide for the contingency which often arises that the voter desires to vote for two or more candidates whose names may be placed opposite a single slide of the machine. To do this the screws 81 are removed and the strips 77 are adjusted to enfold the names of the parties for which the voter desires to cast his vote. It will be found that one of the holes 78 in the strips 77 registers with the pin 58 and is adjusted thereover. If desired, several of these strips 77 may be piled one on the other, so that the one slide 47 could be employed to cast a number of ballots in one operation. It is for this purpose that the series of perforations 82, 82 is provided in both the strip 77 and the slide 47 to form a number of passages for the voting balls when delivered from a chute 32 which would register with any of the holes 82.

As above indicated, the slides 47, 47 are locked in position according to selection by locking bars 57, 57. There is a lock-

ing bar 57 for each of the slides 47. Of these locking bars 57, 57 there are two classes, one having short cut-away portions 82 and the other having longer cut-away portions 83. As stated, the slides 47, 47 may be moved to selecting position only when the cut-away portions 82 or 83 aline with the said slides 47. The locking bars 57 are provided with a series of perforations 84, which are fitted over pins 85, 85, with which a suspension bar 86 is provided. The bar 86 is suspended on vertically-disposed racks 87, the teeth of which are engaged with the teeth provided in the periphery of quadrants 88. The quadrants 88 are mounted at either side of the machine upon a shaft 89 which is journaled at 90, 90 in the sides of the frame of the machine. Fixedly mounted upon the shaft 89 is a disk 91, which is provided with a pointer 92 and an operating handle 93. The pointer 92 rotates over the side of the machine where, in the path of the said pointer, are indicated stations marked by the several names or designations of the parties figuring in the election as parties, having restricted rights or limitations, and for which this machine is adapted to be operated. There is hereby provided means whereby women and certain classes of men voters having residential but not citizenship rights, may be prevented from operating the machine to vote regular or split tickets after gaining admission to the voting booth. The operation of the machine is thus far placed under the control of an inspector of elections or other delegated officer. With the movement of the pointer 92 opposite each of the names, the shaft 89 is rotated to lift the racks 87, 87, and the suspension bar 86, so that the one or the other of the cut-away portions 82, 83 will be raised to permit certain only of the rods 47 to be advanced toward the rear of the machine. Those permitted to be advanced will correspond with the limitations with which the voter is controlled. This selection is made by the inspector, who moves the pointer 92 to indicate the limitations assigned to the voter. These limitations are imposed in the general rule against women voters in various localities. In various States and localities within each State, the restrictions upon women voters is more or less imposed. The section marked C in Fig. 16 of the drawings of the voting table is assigned, as a rule, to this form of voting, and the slides 47 thereon are individually and manually operable. It is to prevent the operation of the remaining slides when the machine is unlocked to accommodate the vote of the restricted voter, that the long cut-away portions 83 are provided. These elongated cut-away portions 83 are arranged to release the slides 47 on the section of the table marked C, and

which, as stated, are adjustable to suit the desires of the restricted voter.

In the extreme forward position of the slides 47, 47, the nipples 61 with the conveyers 32, 32, are disposed over a certain receptacle 94 provided to receive the balls where the voter chooses to vote "blank" on the machine.

When special restrictions are provided, as, for instance, in elections where women are permitted to vote on certain questions, more or less limited, the cam bar 95 is moved by the inspector outward, to rest under the end of the cam rod 96. The cam rod 96 supports a link 97 to which is pivoted a dog arm 98 in which a slot 99 is formed, to have clamped therein a set pin 100. The set pin 100 is disposed to engage the series of recesses 101 (see Fig. 1 of the drawings). The engagement between the pin 100 and the recesses 101 occurs according as the pointer 92 is moved.

Whenever the lever 46 is moved to transfer the balls from the bar 27 to the conveyers 32, the rod 102 throws a latch 103 to one side to permit the rod 104 to drop. The dropped position of the rod 104 is indicated in Fig. 1 of the drawings by dotted lines. In dropping, the rod 104 strikes upon the tail end extension 105 of a hammer 106 adapted to strike a bell 107 with which the machine is provided. The sounding of the bell 107 apprises the inspector that the vote has been cast. The inspector immediately throws the lever 46 to the position shown in full lines in Fig. 1 of the drawings, which advances the set bar 49 to recede all of the slides 47 which have been placed in the selecting position, and at the same time, locks the said selecting bars against further manipulation. Through the extension 108 of the lever 46 and the lever 109 and link 110, the rod 104 is again raised to its suspended position, the latch 103 being actuated to throw under the foot of the said rod 104 whenever thus raised. With this action of the lever 46 the rod 104 is reset, and the machine is in position to be again operated for casting the ballot.

There is provided on one side of the machine, as shown in dotted lines in Fig. 1 of the drawings, a chute 111 for the admission of "irregular ballots." These "irregular ballots" when deposited in the chute 111 are held upon the tail piece 39 of the plate 39, which is normally extended over the opening to the chute 111 (see Fig. 4 of the drawings). In the side of the chute, and just above the plate 39 is a peep hole 112, designed to permit the inspector to see the ballot thus cast. The chute 111 is guided to deliver the so-called "irregular ballots" to a special receptacle. With each throw of the lever 46 to the position shown in dotted lines in Fig. 1, the plate 39 is placed in position

where the opening 113 in plate 39 is brought in alinement with the chute 111, permitting the "irregular" vote to drop, and to be regularly deposited. With the return of the 5 lever to the position shown in full lines, the tail piece of the plate 39 is interposed above the chute 111.

In manipulating the selecting strips 77, 77, so that two or more are embodied, there 10 might be danger of breaking the machine, should the set bar 49 catch the nipples 61 in the frame of the machine, due to carelessness on the part of the voter in not returning the various strips 77 to their proper location. It is to avoid this that I have provided a dog 114, a rod 115 connected therewith, and hangers 116 pivoted upon a rod 117. Whenever two of the strips 77 are 15 upon a slide 47, they engage the rod 117, drawing the pull rod 115 to set the tooth of the dog 114 into the ratchet teeth 118 provided on the upper surface of one of the side arms. This arrests the forward action of the setting mechanism in such manner as to avoid danger to the parts. 20

During the operation of the machine, whenever the tubes 16, 16, in one line become emptied, the inspector by means of the handle 26 rotates the shaft 24 to advance 30 the plate 17 bearing the tubes 16, 16, and a succeeding row of tubes register with the tubular openings in the bar 27.

At the end of the voting, slides 119, 119 are introduced in grooves formed by extending the metal 120, 120, of the top frame holding the receptacles 65, 65. These slides 35 119 are shown as adapted to be permanently in position, having openings 121 to register with the channels 63, 63. When the slides 40 119 are moved to close the receptacles 65, a perforation in the end thereof registers with the end wall of the particular line of receptacles for which that slide is intended, and a T-shaped member 122 is introduced 45 through the perforations. In the end of the T-shaped member 122 is a perforation adapted to receive the hasp of a padlock 123. When the member 122 is thus secured 50 in position, it is impossible to remove the balls from the receptacles 65.

The receptacles 65 are mounted in triple arrangement as shown in Fig. 15 of the drawings. Each tube thereof is constructed in rectangular form, as shown, having a 55 cross section length, slightly less than the diameter of two balls, while the cross section width is slightly greater than one ball. In the front of these tubes are formed open slots 124 through which the balls may be viewed. On the side of the slots is formed a scale 125 whereby the balls may be counted at a glance. It will be noticed in Fig. 60 15, that by reason of the construction giving the cross section dimensions above mentioned, the balls as received in the tubes are

arranged in the alternate and inclined position therein shown. This results in a close packing, convenient for counting. A scale 125 is regulated with regard to the disposition of the balls within the tubes. Further, 70 it will be observed, that the inclined ends 64 of the tubes forming the receptacles 65, are given approximately the same angle assumed by the nesting balls. The result of this action is that, as the balls are introduced from the channels 63 the first tube of the receptacle 65 is filled, the balls therein assuming at the top of the tube approximately the angle of the tops of the tubes. Thus, as the first of the series of tubes 75 becomes filled, the balls at the top thereof form a pathway for the balls leading on to the second of the series of tubes. As the second becomes filled, the balls therein form a pathway leading to the third of the series. 80

In the portion of the machine which might be tampered with, it is covered by a glass panel 126, contained in a frame in the upper rail of which are provided perforations or peep holes 127 through which the 90 voter may get a view of the balls contained in the slide 33 which he is selecting to cast as his ballot.

Having thus described my invention, I claim as new and desire to secure by Letters 95 Patent:

1. A voting machine, comprising a magazine adapted to contain voting devices, stationary receptacles for said voting devices when voted, arranged in serial order to correspond with a selecting table, a plurality of conveyers connected with said magazine and adapted to extend over said receptacles to deliver the voting devices thereto, a selecting table having designations thereon 105 located in serial order to correspond with said receiving receptacles and denoting a choice of the voter, adjustable devices mounted on said table, adapted to indicate a choice of said designations and to adjust 110 the ends of said conveyers to conform with said table, locking devices arranged in gangs to prevent the adjustment of certain of the said adjustable devices, and means for delivering to each of the various conveyers a 115 single voting device simultaneously.

2. A voting machine, comprising a magazine adapted to contain voting devices, stationary receptacles for said voting devices when voted, arranged in serial order to correspond with a selecting table, a plurality of conveyers connected with said magazine and adapted to extend over said receptacle to deliver the voting devices thereto, a selecting table having designations thereon 120 located in serial order to correspond with said receiving receptacles and denoting a choice of the voter, adjustable devices mounted on said table, adapted to indicate a choice of 125 said designations and to adjust the ends of 130

said conveyers to conform with said table, locking devices arranged in gangs to prevent the adjustment of certain of the said adjustable devices, means for controlling 5 said locking devices operable by the inspector only, and means for delivering to each of the various conveyers a single voting device simultaneously.

3. A voting device, comprising a magazine 10 adapted to contain voting devices, stationary receptacles for said voting devices when voted, arranged in serial order to correspond with a selecting table, a plurality of conveyers connected with the said magazine and adapted to extend over said receptacles to deliver the voting devices thereto, adjustable devices extensible over said receptacles connected with said conveyers to place the same over the said receptacles, an adjusting 15 mechanism connected with said adjustable devices to move the same in gangs, selecting devices indicating the gangs to be moved by the said mechanism, and means for delivering to each of the various conveyers a 20 single voting device simultaneously.

4. A voting machine, comprising a magazine embodying a series of tubes arranged in lateral lines, an extracting plate slidably mounted below said tubes and in line therewith and having a series of perforations adapted to aline with said tubes, a plurality of conveyers stationarily mounted below and in line with said perforations in said extracting plate and adapted to extend over receptacles to contain the voting devices when extracted from said magazine, stationary receptacles for said voting devices arranged in serial order to correspond with a selecting 30 table, said receptacles embodying one member indicating no vote, a selecting table having designations thereon located in serial order to correspond with each receptacle and denoting a choice of the voter, selecting devices adjustable on each table and adapted 35 to place the movable ends of said conveyers to deliver the voting devices thereto, and a lever to be operated by the voter to move said extracting plate from alinement with the said tubes to alinement with the said conveyers.

5. A voting machine, comprising a magazine embodying a series of tubes arranged in lateral lines, an extracting plate slidably mounted below said tubes and in line therewith and having a series of perforations adapted to aline with said tubes, a plurality of conveyers stationarily mounted below and in line with said perforations in said extracting plate and adapted to extend over receptacles to contain the voting devices when extracted from said magazines, stationary receptacles for said voting devices when voted, said receptacles being arranged in serial order to correspond with a selecting 50 table, a selecting table having designations

thereon located in serial order to correspond with said receptacles, selecting devices adjustable on said table and adapted to place the movable end of said conveyers in position to deliver to the receptacle corresponding with the designation on said selecting table, means for locking the said selecting devices, and a lever to be operated by the voter to move said extracting plate from alinement with the said tubes to alinement 75 with the said conveyers.

6. A voting machine, comprising a magazine embodying a series of tubes arranged in lateral lines, an extracting plate slidably mounted below said tubes and in line therewith and having a series of perforations adapted to aline with said tubes, a plurality of conveyers stationarily mounted below and in line with said perforations in said extracting plate and adapted to extend over receptacles adapted to contain voting devices when extracted from said magazine, stationary receptacles for said voting devices, arranged in serial order to correspond with a selecting table, a selecting table having designations thereon located in serial order to correspond with said receptacles and denoting a choice of the voter, selecting devices mounted on said table adapted to indicate a choice of said 90 designations and connected to the ends of said conveyers to move the said conveyers to conform with said table, mechanism for returning the said selecting devices to their initial position, and a lever to be operated 95 by the voter to move said extracting plate from alinement with the said tubes to alinement with the said conveyers.

7. A voting machine, comprising a magazine embodying a series of tubes arranged in lateral lines, an extracting plate slidably mounted below said tubes and in line therewith and having a series of perforations adapted to aline with said tubes, a plurality of conveyers stationarily mounted below and in line with said perforations in said extracting plate and adapted to extend over receptacles to contain said voting devices when extracted from said magazine, a lever to be operated by the voter to move said extracting plate from alinement with said tubes to alinement with the said conveyers, and an alarm adapted to be actuated by the said lever.

8. A voting machine, comprising a magazine embodying a series of tubes arranged in lateral lines, an extracting plate slidably mounted below said tubes and in line therewith and having a series of perforations adapted to aline with said tubes, a plurality of flexible conveyers stationarily mounted below and in line with said perforations in said extracting plate and adapted to extend over receptacles to receive said voting devices when extracted 120 125 130

from said magazine, a lever to be operated by the voter to move said extracting plate from alinement with said tubes to alinement with the said conveyers, and a mechanism 5 to return said plate in line with said tubes, adapted to be operated by the inspector of elections.

9. A voting machine, comprising a magazine embodying a series of tubes arranged 10 in lateral lines, an extracting plate slidably mounted below said tubes and in line therewith, having a series of perforations adapted to aline with said tubes, a plurality of conveyers stationarily mounted below and 15 in line with the said perforations in said extracting plate and adapted to extend over receptacles to contain said voting devices when delivered from said magazine, a lever 20 to be operated by the voter to remove said extracting plate from alinement with said tubes to alinement with the said conveyers, an alarm adapted to be actuated by said lever, and mechanism to return said plate in 25 line with said tubes and to reset said alarm, adapted to be operated by the inspector of elections.

10. A voting machine, comprising a magazine embodying a series of tubes arranged 30 in lateral line, a supporting plate for said tubes having a series of perforations adapted 35 to aline with the said tubes, a shifting mechanism adapted to move the said tubes to aline the tubes of successive lines with the perforations in said supporting plate, an extracting plate slidably mounted below said 40 supporting plate and having a like number of perforations adapted to aline with perforations in said supporting plate, a guide member for said extracting plate, stationarily mounted and having a series of perforations 45 out of line with the perforations in said supporting plate, a plurality of flexible conveyers extended from the perforations in said guide member, and a lever to be operated by the voter to move said extracting plate from alinement with the perforations in said supporting plate to alinement with the perforations in said guide member.

50 11. A voting machine, comprising a magazine embodying a series of tubes arranged 55 in lateral lines, a supporting plate for said tubes, having a series of perforations adapted to aline with said tubes, a shifting mechanism adapted to move the said tubes to aline the tubes of successive lines with the perforations in said supporting plate, an operating device for actuating said shifting mechanism and operated by the inspector of 60 elections, an extracting plate slidably mounted below said supporting plate and having a like number of perforations adapted to aline with the perforations in said supporting plate, a guide member for said 65 extracting plate, stationarily mounted and

having a series of perforations out of line with the perforations in said supporting plate, a plurality of flexible conveyers extended from the perforations in said guide member, and a lever to be operated by the voter to move said extracting plate from alinement with the perforations in said supporting plate to alinement with the perforations in said guide member. 70

12. A voting machine, comprising a magazine adapted to contain voting devices, stationary receptacles for said voting devices when voted, arranged in serial order to correspond with the selecting table, a plurality of flexible conveyers connected with said magazine and adapted to be adjusted to deliver to said receptacles, a plurality of slides 75 guidably mounted on said table, adapted to be locked in inoperative position, partitions between said slides adapted to be removed, means for removing the said partitions, a plurality of selecting strips connected to the said conveyers and adapted to be adjustably attached upon different members of a group of said slides when the said partitions are 80 removed said slides having index devices for adjustment with the said designations on the selecting table, and means for delivering to each of the said conveyers a single voting 85 device simultaneously. 90

13. A voting machine, comprising a magazine adapted to contain voting devices, stationary receptacles for said voting devices when voted and arranged in serial order to correspond with the selecting table, a plurality of flexible conveyers connected with said magazine and adapted to be adjusted to deliver to said receptacles, a plurality of slides 100 guidably mounted on said table adapted to be locked in inoperative position, a plurality of selecting strips connected to the said conveyers and adapted to be adjustably attached upon different members of a group of said slides and with reference to the said designations on the selecting table, means 105 for resetting the said slides after being moved for voting, a safety mechanism to prevent the resetting of said slides when more than one of said selecting strips are mounted upon said slides, and means for delivering to 110 each of the said conveyers a single voting device simultaneously. 115

14. A voting machine, comprising a magazine adapted to contain voting devices arranged in regular order for regular voting, 120 a series of conveyers adapted in number to the candidates and questions, to deliver the voting devices to suitable receptacles when cast, selecting devices for regulating the receptacles to which said voting devices are delivered by said conveyers, an extracting mechanism for delivering from the said magazine to each of the said conveyers each 125 a single voting device simultaneously, said mechanism being adapted to be operated by 130

the voter, a receptacle for receiving irregular votes, a device to close said receptacle, and a mechanism adapted to be operated by the inspector of elections to return the said extracting mechanism to its initial position and remove said device which closes the receptacle for receiving irregular votes.

In testimony whereof I have signed my name to this specification in the presence of two subscribing witnesses.

CLARENCE LEICESTER LORRAINE.
